(57) **CLAIM**

The ornamental design for a snow brush handle, as shown and described.

DESCRIPTION

FIG. 1 is a perspective view of a snow brush handle, the brush head and scraper being shown in broken lines to illustrate environmental structure of the handle that forms no part of the claimed design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is a bottom plan view thereof.
